UNITED STATES PATENT OFFICE.

DE WITT C. LAMBSON, OF WALLINGFORD, CONNECTICUT.

DOOR HOLDER AND LATCH.

Application filed May 8, 1925. Serial No. 28,789.

To all whom it may concern:

Be it known that I, DE WITT C. LAMBSON, a citizen of the United States, and a resident of Wallingford, county of New Haven, 5 State of Connecticut, have invented certain new and useful Improvements in Door Holders and Latches, of which the following is a specification.

This invention relates to a combined door-10 stop holder and door latch particularly adapted to be used in connection with garage doors, although not restricted to such use.

An important object of the invention is 15 to provide an improved device of the character mentioned for retaining the door in an open position, and for also latching the door in closed position, in combination with operating means for so actuating the device 20 as to release the locking device and thus permit the door to be readily moved from its open position to its closed position and vice versa.

Other objects and certain advantages of 25 the invention will become apparent from the following description when taken in connection with the accompanying drawings in which—

Figure 1 is a view in elevation showing 30 the device applied to a door and so positioned as to lock the door in closed position.

Figure 2 is a fragmental view of a door in elevation, showing the device so positioned as to retain the door in open position.

Figure 3 is a horizontal sectional view 35 taken on line 3—3 of Figure 1, with the device and door shown also in dotted line positions corresponding to their respective full line positions shown in Figure 2.

Figure 4 is an enlarged view, in elevation, 40 of the device in its door locking position, as shown in Figure 1.

Figure 5 is an enlarged view, in elevation, 45 of the device in its door holding position, as shown in Figure 2.

Figure 6 is a detail view in end elevation, 50 showing the relation of the locking elements, when the door is in closed position and locked.

Figure 7 is a similar view, showing the 55 locking device in raised position to allow the door to be opened.

Figure 8 is a detail view, in end elevation, 60 showing the angular arm of an operating rod and how the device is pivotally connected to a supporting bracket.

Figure 9 is a detail view showing, in elevation a bolt structure, as attached to the bottom of the door and adapted to cooperate with the door holder. 60

Figure 10 is a fragmental plan view of a door, having the bolt structure, shown in Figure 9, associated therewith.

In the drawings, wherein for the purpose of illustration is shown what I at present 65 consider the preferred form of my invention, the numeral 5 indicates a door facing or frame to which a door 6 is adapted to be connected, as by means of hinges 7. The device for locking the door in its closed position, as shown in Figure 1, and for retaining or holding the door in its open position, as shown in Figure 2, comprises an elongated tube or locking element 9, one end of which is provided with a lip 10 adapted for 70 pivotal connection to a bracket 11 suitably connected to the door, as by means of screws 12. This tube is cut away at the other end, as shown, thus providing a notch 13 and forming a pair of depending ears 14. 80 Within the tube 9 there is arranged an elongated rod or shaft 15, one end of which is bent to provide a lever 16, and the other end of which is journaled in a downwardly bent lip 17 at the end of the tube. The 85 journaled end of the rod is bent over upon itself, thereby forming a lifting finger or cam 18 which extends along the outside of the tube for an appreciable distance and is, at its end, bent in towards the tube to provide a cam finger 19 which insures unobstructive movement of the notched end of the tube from its locking position shown in Figure 4 to its holding position shown in Figure 5 as will hereinafter more clearly appear.

To the door facing 5, there is connected a bracket 20, the depending arm 21 of which functions as a suitable stop for the free end of the rod 9 when being moved from its position shown in Figure 2 to its position shown in Figure 1. A catch having a base 22 is suitably connected to the door 6 and is provided with an angular projecting portion 23 having a notch 24 formed therein and provided at its outer end with a bevel or inclined face 25 over which the free end of the tube 9 is adapted to slide as the door approaches its closed position. 105

To the frame 5, relatively near the pivoted end of the tube 9, when the door is in its closed position, there is suitably connected 110

a guide or supporting element 26 through which the tube is adapted to slide when the door is being moved from one position to the other. This guide functions as a means adapted to cooperate with the notched end of the tube 9 to hold the door in its open position. In moving the door from its closed position to its open position, the tube 9 is free to slide or move through the guide until the door has assumed its outermost position, shown in Figures 3 and 5. Then the notch 13, after the finger 18 has been directed into the guide 26 by the cam 19, allows the free end of the tube 9 to so drop as to permit the guide 26 to enter the notch 13. As the tube 9 drops to its holding position best shown in Figure 5, the finger 18, due to the weight of the tube 9, is lifted to the position shown in Figure 5, in which position it remains until it is so rotated, with respect to the tube 9, as to lift or elevate the free end thereof and thus free the guide 26 from the notch to allow the door to be moved from its open position to its closed position. In order to rotate the shaft 15, with respect to the tube 9, a suitable chain 27 may be employed, which chain is connected to the outer end of the arm 16. After rotating the shaft or rod 15 and thereby so lifting the free end of the tube 9 as to disengage the guide 26 from the notch 13, the door 6 may be moved from its open position to its closed position, and as a result of this movement the tube 9 is permitted to freely slide through the guide 26. As the door approaches its closed position, the free end of the tube is moved towards the bracket 20, meeting the beveled end 25 of the catch and sliding over the same into the locking position shown in Figure 6, just as the door reaches its closed position. Upon completion of the lateral movement of the tube 9, the free end thereof drops under its own weight, so that the catch enters the notch 13 and the arm 18 rests upon the top of the extension 24 of the catch, while the notched free end of the tube is positioned in the notch 24 of the catch. With the free end of the tube 9 positioned as shown in Figure 6, it is apparent that the door 6 is locked against opening, inasmuch as the extension 24 cannot move for the reason that the tube 9 is held intermediate the depending arm 21 of the bracket 20 and the extension 24 of the catch. To release the locking engagement of the tube 9 with the catch, the shaft 15 may be rotated with respect to the tube by means of the chain 27 to effect relative movement between the finger 18 and the tube whereby the finger 18, due to its engagement with the extension 24 of the catch lifts the free end of the tube 9 to the position shown in Figure 7, thereby permitting the free end of the tube to pass unobstructed over the top of the extension 24 of the catch and at

the same time permitting the extension 24 to pass through the notch 13 as the door is opened.

An auxiliary locking device in the form of a bolt, indicated as a whole in Figure 1 by the numeral 29, may be provided. This bolt comprises a suitable guide 30 which is secured to the door 6 and carries a reciprocating locking element 31 mounted in the laterally extending flanges 32 of the bracket and adapted to engage a keeper 33 which may be secured, by any suitable means, to the threshold of the door. The locking element 31 is provided with a yoke 34 adapted for the reception of a crank arm 35 carried at one end of an operating shaft 36 which, at its other end, is journaled in suitable brackets 37 and 38 and is provided with an arm 39 adapted to be connected to the chain 27. The locking element 31 may be released from the keeper 33 through the shaft and chain connections simultaneously with the release of the notched end of the tube 9 from the catch extension 23.

Having thus described my invention, I claim:

1. A combined door-stop holder and latch comprising a locking element adapted for pivotal connection to a door, means arranged intermediate the ends of said locking element over which said locking element is adapted to move when opening and closing said door and into holding engagement with which said locking element is adapted to move upon opening said door, and a catch into locking engagement with which said locking element is adapted to be moved when closing said door.

2. A combined door-stop holder and latch comprising a locking element adapted for pivotal connection to a door, means arranged intermediate the ends of said locking element over which said locking element is adapted to move when opening and closing said door and into holding engagement with which said locking element is adapted to be moved upon opening said door, a catch into locking engagement with which said locking element is adapted to move when closing said door, and operable means associated with said locking element for releasing the locking engagement of said holding and locking element with the first named means and said catch respectively.

3. A combined door-stop holder and latch comprising a locking element adapted for pivotal connection to a door, a supporting element arranged intermediate the ends of said locking element over which said locking element is adapted to move when opening and closing said door and into holding engagement with which said locking element is adapted to move upon opening said door, a catch into locking engagement with which said locking element is adapted to move up-

on closing said door, and operable means associated with said locking element for releasing the holding and locking engagement of said locking element with said support and catch respectively, said operable means being in the form of a rod having a finger adapted to cooperate with said support and catch for lifting said locking element out of holding and locking engagement with said support and catch respectively.

4. A combined door-stop holder and latch comprising a locking element having a notch at one end thereof and adapted for pivotal connection at its other end to a door, a supporting element arranged intermediate the ends of said locking element over which said locking element is adapted to move when opening and closing said door, said

20 notch being adapted for the reception of said supporting element upon opening said door to hold said door in its open position, a catch carried by said door into locking engagement with which said locking element is adapted to move upon closing said door, and operable means associated with said locking element for so lifting said locking element as to free said support from said notch and for so lifting said locking element 25 as to release the locking engagement of said locking element with said catch.

5. A combined door-stop holder and latch comprising a locking element adapted for pivotal connection to a door, means arranged intermediate the ends of said locking element over which said locking element is adapted to move when opening and closing said door and into holding engagement with which said locking element is adapted to 30 move upon opening said door, a catch into locking engagement with which said locking element is adapted to move when closing said door, and a stationary bracket against which said locking element is adapted to abut when an attempt is made to open said door while locked in its closed position.

6. A combined door-stop holder and latch comprising a locking element having a notch at one end adapted for pivotal connection 35 at its other end to a door, a stationary supporting element arranged intermediate the ends of said locking element over which said locking element is adapted to move when opening and closing said door, said supporting element being adapted to enter said notch upon opening said door, a catch carried by said door and adapted to cooperate with the notched end of said locking element when said door is closed, and operable means associated with said locking element for releasing the engagement of said locking element with said supporting element and said catch.

7. A combined door-stop holder and latch

comprising a locking element having a notch 65 at one end and adapted for pivotal connection at its other end to a door, a stationary supporting element positioned intermediate the ends of said locking element over which said locking element is adapted to move 70 when opening and closing said door, said locking element being adapted to enter said notch upon opening said door, a catch carried by said door and adapted to cooperate with the notched end of said locking element when the door is closed, and a stationary bracket against which said locking element is adapted to abut when an attempt is made to open said door, and operable means associated with said locking element for releasing the engagement of said locking element with said supporting element and said catch.

8. A combined door-stop holder and latch comprising a locking element adapted for 85 pivotal connection to a door, means arranged intermediate the ends of said locking element over which said locking element is adapted to move when opening and closing said door and into holding engagement with which said locking element is adapted to move upon opening said door, a catch into locking engagement with which said locking element is adapted to move when closing said door, operable means associated with 90 said locking element for releasing the locking engagement of said locking element with the first named means and said catch respectively, an auxiliary locking device for locking said door in its closed position, and means for actuating said operable means and auxiliary locking device simultaneously.

9. A combined door-stop holder and latch comprising a locking element having a notch at one end thereof and adapted for pivotal 105 connection at its other end to a door, a stationary yoke positioned intermediate the ends of said locking element over which said locking element is adapted to move when opening and closing said door, said yoke being adapted to enter said notch upon opening said door, a catch carried by said door, said catch being provided with an extension and a beveled face over which said locking element is adapted to move to establish locking engagement with said extension, a stationary bracket against which said locking element is adapted to abut when an attempt is made to open said door while said locking element is maintained in locking engagement with said extension, and operable means associated with said holding and locking element for releasing the locking engagement of said locking element with said yoke and catch respectively.

In testimony whereof, I have affixed my signature to this specification.

DE WITT C. LAMBSON.
